ROOFING NAIL

Edward Caughey, Norwich, Conn.

Application March 27, 1933. Serial No. 663,061

1 Claim. (Cl. 85—30)

In the present invention I provide a roofing nail designed to positively prevent casual displacement of the nail from the roofing materials when the latter expand.

5 It is well known in the art that roofing nails become loosened in the roofing material in a relatively short period of time and since these nails are necessarily of short length, their effectiveness is manifestly impaired unless the nails 10 are periodically redriven into the roof. With the present nail, a permanent fastening means for the roof is provided, which will not loosen or become displaced regardless of atmospheric or weather conditions.

15 A further object of the invention is to provide a roofing nail with an enlarged entering terminal, the margins of which are interrupted to provide work-engaging protrusions.

Other objects of the invention will be apparent 20 from the following description of the present preferred form thereof, taken in connection with the accompanying drawing, wherein

Fig. 1 is a side elevational view of a roofing nail, constructed in accordance with the present 25 invention, illustrating its application, the face of the nail being shown.

Fig. 2 is a similar view, looking at the edge of the nail; and

Fig. 3 is a perspective view of a roofing nail, 30 per se, constructed in accordance with the present invention.

In order to illustrate the application of the present invention, I have shown a portion of a roof 4 composed of the usual beams or timbers, 35 with roofing material superimposed thereon. It is well known at the present time that the roofing material is secured by relatively short nails having shanks circular in cross-section, the peripheries of which are roughened or serrated. The 40 nails are driven through the roofing material into the supporting beams or timbers in a manner well-known in the art. In the present invention, the nail is used in the same manner by being driven through the roofing material and into the 45 supporting beams of the roof, to which latter the nail is locked to prevent accidental withdrawal of the nail.

As illustrated to advantage in Fig. 3, the shank 5 of the nail is circular in cross-section and is 50 provided at one end with a head 6, while the opposite end is flattened to provide a substantially

wedge shaped entering terminal 7. Said terminal 7 has the lateral margins thereof intermediately interrupted by incisions or recesses 8, one of which is formed in each side of said terminal. Preferably, each incision is disposed obliquely 60 to the longitudinal axis of the nail and a portion of each side of the nail projects outwardly from a wall of each incision to provide a lateral protruding tooth or terminal 9. Consequently, when the nail is driven into the roof, as shown in Figs. 65 1 and 2 of the drawing, the protrusions 9 will be imbedded into the roof beam or timber.

After the nail of the present invention has been completely driven into the roof as shown in Figs. 1 and 2, I have found that it cannot 70 be removed from the roof with a pulling pressure in excess of four and three-quarter pounds, whereas an ordinary roofing nail can be removed with a pulling pressure of approximately one and three-quarter pounds. While the nail of the present invention is especially adapted to replace 75 roofing nails which have been casually displaced in that the nails of the present invention may be driven with facility into the openings, or recesses formed by the displaced nails, it is of course, 80 to be understood that the nail of the present invention may also be used in new work. The pointed entering terminal of the nail with the relatively large head commonly employed in roofing nails makes driving of the nail into the material possible without much more resistance than that given by an ordinary roofing nail. The contour of the entering terminal of the nail facilitates movement of the nail through the material, while the protruding teeth 9 at the 85 sides of the entering terminal makes removal of the nail very difficult.

Various changes may be made in the present invention, within the scope of the appended claim. 95

What is claimed is:

A roofing nail including a headed shank the work engaging end of which is flat in cross-section and the margins curved to provide a sharp pointed entering terminal, said curved margins having incisions therein disposed obliquely to the long axis of the shank, the lower wall of each incision projecting beyond the upper wall of the latter to provide an upwardly extending tooth. 100

EDWARD CAUGHEY.
